(57) **CLAIM**

The ornamental design for a children's medical privacy sleeve, as shown and described.

DESCRIPTION

FIG. 1 is a front view of the children's medical privacy sleeve

FIG. 2 is a rear view of the children's medical privacy sleeve

FIG. 3 is a top view of the children's medical privacy sleeve

FIG. 4 is a right side view of the children's medical privacy sleeve

FIG. 5 is a left side view of the children's medical privacy sleeve; and,

FIG. 6 is a front view of the children's medical privacy sleeve on an arm.

The broken line showing an arm is included for the purpose of illustrating environment and forms no part of the claimed design.
